UNITED STATES PATENT OFFICE

ALFRED J. HEYER, OF ST. LOUIS, MISSOURI, ASSIGNOR, BY MESNE ASSIGNMENTS, TO
HUSSMANN-LIGONIER COMPANY, OF ST. LOUIS, MISSOURI, A CORPORATION OF
DELAWARE

COUNTER REFRIGERATOR

Application filed August 26, 1928. Serial No. 584,425.

This invention relates to refrigerators, and more particularly to those known as show-case refrigerators which are arranged to display the contents thereof for sale.

5 In some places where meat and other perishable goods are marketed on a fairly large scale, it is found that so-called mechanical refrigeration is more economical than the use of ice for cooling and preserving the 10 perishable goods. While mechanical refrigeration has ordinarily been applied only to such installations where perishable goods were to be preserved in storage for an extended period, more recent developments in 15 refrigeration have applied the mechanical process also to smaller installations. It is thus found desirable to be able to apply the mechanical process to the display counters and show-case refrigerators of a small retail 20 market.

One of the objects of this invention, therefore, is to provide a show-case or display counter refrigerator with expansion coils and other appurtenances suitable for the application 25 of mechanical refrigeration thereto.

Another object of this invention is to provide a counter refrigerator with a cooling system including a brine tank in which an expansion coil is immersed which may be connected to mechanical refrigerating apparatus.

Another object of this invention is to provide a counter refrigerator with a cooling system having an expansion coil immersed in a brine tank, said brine tank being constructed 30 and arranged to set up circulating currents of air in the cooling chamber so as to effectively reduce the temperature of the goods stored in said chamber.

Further objects will appear from the detail description taken in connection with the accompanying drawing, in which:

Figure 1 is a cross sectional plan view of a counter refrigerator embodying this invention;

45 Figure 2 is a section on line 2—2, Figure 1;

Figure 3 is a section on line 3—3, Figure 2; and

Figure 4 is a perspective view showing a refrigerator embodying this invention.

50 Referring to the accompanying drawing,

the refrigerator illustrated comprises an oblong box 1 provided with glass panels 2 for displaying the contents of the cooling chamber 3 within the box. The chamber 3 is provided with shelves 4 for holding the goods 55 to be displayed. At one or both ends of the refrigerator is a refrigerating chamber 5 within which is suitably mounted a brine tank 6.

The tank 6 is an ordinary rectangular tank 60 suitably arranged for holding brine but is provided with transverse air ducts or flues 7. Any suitable number and arrangement of flues may be used. Arranged within the tank 6 and between the flues 7 is an expansion coil 65 8. The coil 8 is ordinarily constructed by coiling up a pipe of suitable material, such as copper, into a helical form so as to compact a considerable length of pipe into a small space. In the device shown in the illustration, two such coils are constructed of a continuous length of pipe and placed side by side in the tank 6. The ends of the coil pipe are brought out of the tank 6 through suitable bushings 9. Nipples 10 may be connected to the coils at the bushings 9 and to the nipples 10 suitable connections 11 may be made to the exterior of the refrigerator for connection to the refrigerating machine, not shown.

When two or more refrigerating units are used in the same counter, said units may be connected together by expansion pipes 12 passing longitudinally along the bottom of the refrigerator and providing an auxiliary 85 refrigerating element. The connection is so made that the refrigerating medium will flow through the various coils in series.

In the operation of this refrigerator, suitable connections are made at 11 to a refrigerating machine, not shown, an expansion valve 13 being placed at the point where the refrigerating medium enters the refrigerator. Suitable brine, such as a solution of salt or calcium chloride, or other suitable material 95 is placed in the tank or tanks 6 which are filled to such a point that the coil 8 is completely submerged. The refrigerating medium, such as, for instance, ammonia, is brought to the expansion valve 13 usually in a liquid 100

form. The valve 13 admits the liquid to the connections 11 whereupon it vaporizes and expands through the coil 8 and the pipes 12. By the well known properties of fluids and 5 gases, the vaporization of the liquid at the expansion valve as well as its subsequent expansion throughout the piping system is accompanied by the absorption of a great amount of heat by the refrigerating medium. 10 The heat absorbed is taken from the material surrounding the coils, namely the brine in the tank 6. This operates to cool the brine to a low temperature. In ordinary operation a temperature somewhat below the freezing 15 point of water is maintained. The expanded gas is drawn out of the piping system at the outlet connection 11 and returned to the refrigerating machine by which it is compressed and again liquefied for delivery to the 20 expansion valve 13 whereupon the cycle is repeated continuously during the operation of the machine.

When the brine in the tank 6 has been cooled to a low temperature, such a tank constitutes a refrigerating unit which will be effective in chilling the air that comes in contact with it. The tank is arranged in the chamber 5 so as to leave space for the circulation of air therearound and over and in rear 30 of the same. As the air becomes chilled, it falls toward the floor of the refrigerator. Air passing downwardly behind or in rear of the tank 6 will flow into the flues 7 and becoming further chilled by contact with the 35 walls of said flues, will flow out at the forward end thereof and fall to the floor of the cooling chamber. The flues 7 may be given a slight slope so as to facilitate the flow of air therethrough. The chilled air flowing downward along the refrigerating unit and pouring forth from the flues 7 forces the warmer air of the cooling chamber 3 to raise to the top of said chamber, passing along the top toward the refrigerating units, to be chilled 40 in its turn and caused to fall to the floor of the chamber. Thus a definite circulation is set up within the refrigerator. The heat contained in the goods put into the cooling chamber for preservation is transferred to 45 the air in that chamber, which thereupon transfers it to the refrigerating unit and by carrying on the above described circulation a continuous supply of chilled air is passed around the goods, thereby reducing their temperature to that of the atmosphere of the 55 box.

It will, therefore, be seen that in accordance with this invention a counter refrigerator is provided embodying an elongated show 60 case provided with transparent panels so that the provisions, etc. in the show case are visible and in full view. A brine-receiving unit or tank is, however, mounted at one end of the show case and this has an expansion coil 65 together with refrigerating medium con-

nections to the coil. This unit is, however, so constructed and arranged and the expansion coil is so arranged and its connections are so made, that a circulation of air is promoted through the unit and along the back 70 thereof; furthermore the unit faces the show case and is in aerial communication with the show case compartment. Accordingly a current of air is caused to circulate in a path from the bottom of the unit along the bottom 75 of the show case and in a return path along the top of the show case to the top of the unit.

In cases where the counter is of considerably extended length so that it becomes necessary to place a refrigerating unit at each end, 80 air currents must be set up in such a way that the air will be carried to all parts of the box, even to the middle thereof between the two refrigerating units. The pipes 12 connecting the two units shown in the illustration 85 pass along the floor of the cooling chamber and serve to maintain a region of cold along the lower part of said chamber. Thus the chilled air is induced to travel along the floor of the chamber to the middle thereof. 90 In this way the flow of cold air may be extended so as to reach even the goods placed at a distance from the refrigerating units.

It will, therefore, be seen that the invention 95 accomplishes its objects. An expansion refrigerating unit is arranged at the end of the show case (or at each end of the show case), but this unit is so constructed and arranged as to cause a current of air to circulate in a path from the bottom of the unit, along the 100 bottom of the show case, and in a return path along the top of the show case to the top of the unit. This unit is therefore, not only placed out of the way of the provisions, but a clear space is left so that the provisions may 105 be viewed through the transparent panels. The circulation is further in such a direction that every part of the show case compartment will be subjected to the cooling action of the refrigerated current of air, even though the 110 show case be considerably extended as is necessary in modern meat markets. Moreover this direction of the current of air along the show case prevents losses when the doors are opened, in that the current of air is parallel 115 to the door opening, and will not, therefore, issue transversely; losses are, therefore, avoided. The cooling is, therefore, by circulation and accordingly the provisions may be piled solidly on the shelves since it is not 120 necessary to depend upon rising and falling currents of air, as is the case where refrigerating pipes are arranged along the bottom or top, or even sides of the show case. More- 125 over the obstructions due to the presence of such pipes when arranged along the show case, together with the attendant drippings of condensed moisture are avoided. In accordance with this invention there is, therefore, an intensive refrigerating unit of the ex-

pansion type arranged at one or both ends of the show case, and this in connection with the arrangement permitting circulation, as described, enables the space required for the unit to be reduced to a minimum so that the display space may be increased to a maximum.

It is obvious that various changes may be made in details of construction without departing from the spirit of this invention; it is, therefore, to be understood that this invention is not to be limited to the specific details shown and described.

Having thus described the invention, what is claimed is:

1. A counter refrigerator comprising, an elongated show case provided with transparent panels, a brine-receiving unit having an expansion coil and mounted at one end of the show case, an auxiliary refrigerating element extending along the bottom of the show case, and refrigerating medium connections to said coil, said unit being constructed and arranged to promote circulation of air therethrough and along the back thereof, and said unit facing the show case and being in aerial communication with the show case compartment, whereby a current of air is caused to circulate in a path from the bottom of said unit along the bottom of the show case and in a return path along the top of the show case to the top of said unit.

2. A counter refrigerator comprising, an elongated show case provided with transparent panels, a brine-receiving unit at each end of the show case, an expansion coil for each unit, an auxiliary refrigerating element extending along the bottom of said show case, and refrigerating medium connections to said coils, each of said units being constructed and arranged to promote circulation of air therethrough and along the back thereof, and each of said units facing the show case and being in aerial communication with the show case compartment, whereby a current of air is caused to circulate in a path from the bottom of each unit along the bottom of the show case and in a return path along the top of the show case to the top of said unit.

3. A counter refrigerator comprising, an elongated show case provided with transparent panels, a brine-receiving unit at each end of the show case, an expansion coil for each unit, an auxiliary expansion element extending along the bottom of said show case and connecting said coils, and refrigerating medium connections to said coils, each of said units being constructed and arranged to promote circulation of air therethrough and along the back thereof, and each of said units facing the show case and being in aerial communication with the show case compartment, whereby a current of air is caused to circulate in a path from the bottom of each unit along the bottom of the show case and in a

return path along the top of the show case to the top of said unit.

4. A counter refrigerator comprising, an elongated show-case provided with transparent panels, an expansion refrigerating unit mounted at one end of said showcase, an auxiliary refrigerating element arranged in the bottom of said show case, and refrigerating medium connections to said unit, said unit and said element being constructed and arranged to cause a current of air to circulate in a path from the bottom of said unit along the bottom of said show-case and in a return path along the top of the show-case to the top of said unit.

5. A counter refrigerator comprising, an elongated show-case provided with transparent panels, an expansion refrigerating unit mounted at each end of said showcase, an auxiliary refrigerating element arranged in the bottom of said show-case, and refrigerating medium connections to said units, said units and said element being constructed and arranged to cause a current of air to circulate in paths from the bottom of each unit along the bottom of said show-case and in a return path along the top of the show-case to the top of each unit.

In testimony whereof I affix my signature this 6th day of July, 1922.
